UNITED STATES PATENT OFFICE.

OSCAR M. STEPPACHER, OF PHILADELPHIA, PENNSYLVANIA.

STARCH HEATER OR TABLE.

1,094,175.

Specification of Letters Patent. Patented Apr. 21, 1914.

Application filed March 12, 1913. Serial No. 753,691.

To all whom it may concern:

Be it known that I, OSCAR M. STEPPACHER, a citizen of the United States, residing in the city and county of Philadelphia, State 5 of Pennsylvania, have invented a new and useful Starch Heater or Table, of which the following is a specification.

In laundries, as usually equipped, it is necessary to keep a number of starch receptacles readily accessible and at the proper 10 temperature in order to attain the best results, and there has heretofore been considerable difficulty in providing a suitable apparatus for conveniently supporting such 15 starch receptacles and keeping the contents of the same uniformly heated to the desired degree.

By my present invention, I provide a novel construction of a heating table, where- 20 in provision is made for supporting a plurality of pails or kettles in such a manner that the same are convenient of access to the operators, said kettles at the same time being simultaneously heated by a suitable 25 steam-receiving pipe within the water-receiving body or tank of the apparatus, the sides, end and top thereof being constructed of wood so as to prevent an undue radiation of heat, while the top of the apparatus is 30 exteriorly covered with a sheathing of metal which reinforces said top and strengthens the walls of the opening in the top member in which the pails or other vessels are inserted, said sheathing being also adapted to 35 form a starching-table.

To the above ends, my invention consists of a novel construction of a steam starch heater or table, the principal features of which will hereinafter be fully set forth 40 and particularly pointed out in the claims.

For the purpose of illustrating my invention, I have shown in the accompanying drawings one form thereof which is at present preferred by me, since the same has been 45 found in practice to give satisfactory and reliable results, although it is to be understood that the various instrumentalities of which my invention consists can be variously arranged and organized and that my invention is not limited to the precise arrange-

ment and organization of these instrumentalities as herein shown and described.

Figure 1 represents a longitudinal sectional view of a steam starch heater or table embodying my invention certain of the parts 55 being shown in elevation, the section being taken on line $x-x$ Fig. 2. Fig. 2 represents a plan view of Fig. 1, certain of the parts being broken away for clearness of illustration. Fig. 3 represents a section on 60 line $y-y$ of Fig. 2. Fig. 4 represents a perspective view of a detached portion.

Similar numerals of reference indicate corresponding parts in the figures.

Referring to the drawings, 1 designates 65 my novel construction of a steam starch heater or table, the same comprising the bottom portion 2 which is rabbed or otherwise secured to the side walls 3, and the end walls 4, said sides, ends and bottom being 70 held in assembled position by any suitable transverse fastening devices, as the bolts or the like 5, said sides, ends and bottom forming a hollow, elongated or trough-shaped receptacle or tank, said bolts 5 passing 75 through plates 6 which are placed against the sides 3 and serve to strengthen the latter while also forming seats for the heads and nuts of said bolts to prevent the same from breaking through said sides. The box 7 is 80 adapted to be filled to about the level indicated in Fig. 1.

8 designates the top of the heater which extends beyond the sides 3 and is preferably made of wood, upon which is placed the cop- 85 per or other metallic covering or sheathing, 9, the latter comprising the table proper on which the starching of goods is accomplished, it being only comparatively warm owing to the poor heat non-conducting nature 90 of the wooden top 8 below it. Said sheathing or covering extends to the extreme edges of said top which extends beyond the sides of the body of the device so as to prevent the surplus starch from flowing down said 95 sides, and the hands of the worker will not contact with the wood of the top and body and so will be removed from liability of being subjected to splinters, while the metal covering forms a smooth surface of metal 100

as the starching table, as above stated, there being a plurality of openings, as 10 provided over the tank 7 within which are supported the starch receiving kettles 11, the latter 5 being of such size as to fit snugly in the openings 10, and being provided with laterally-extending flanges or ears 12, which rest directly upon said metallic covering 9, as will be understood from Figs. 1 and 3.

10 13 designates a steam inlet pipe wherein the steam is conducted ordinarily at about ninety pounds pressure, said steam passing thence through a reducing valve 14 into the pipe 15, where the pressure is reduced to about ten pounds and thence passing through the safety valve 16 and branch 17^x into the loop formed by the branches 17, 18 and 19, the discharge from said branch 19 taking place through the outlet pipe 20 into the steam trap 21. Said pipe 13 is firmly supported on brackets 16^x within the box. The steam loop formed by the branches 17, 18 and 19 is located within the water contained in the tank 7, and said water can be readily 25 withdrawn according to requirements, by proper manipulation of the valve 22 in the drain pipe 23. The entire apparatus can be supported in any suitable manner, but I have shown in the present instance supporting legs or frame work 24 employed, which can be secured to the sides 3 in any suitable manner, as will be evident.

30 As shown in Fig. 4, the end walls 4 are rabbeted into the side walls 3, and when the nuts on the bolts 5 are properly screwed-up, the rabbeted joints of said side and end walls are closed tightly, this being specially necessary as the water in the tank is highly heated by the steam and so leakage at said 35 joints otherwise is likely to occur is prevented. Then as the ends of the side walls 3 are extended beyond the end walls 4 and the extensions are pierced with openings for the passage therethrough of the bolts 5, said 40 openings are outside of the water space of the tank and so are removed from causing leakage of the tank, and the bolts are removed from water and steam, the effect of which is evident.

45 50 The operation is as follows:—The water having been introduced into the tank 7 by any suitable means, and the valve 26 having been opened, it will be apparent that steam at the desired pressure and temperature will be conducted through the loop formed by the branches 17, 18 and 19, and the water contained within the tank having been heated to the desired temperature, through the medium of the steam loop, the starch 55 receptacles 11 will at all times, also, be heated to the proper temperature, and will be supported in a place convenient of access to the operators. When it is desired to shut off the supply of heat, the same can be done

60 by proper manipulation of the valve 26 and, 65 the apparatus can be readily drained by proper manipulation of the valve 22 in the drain pipe 23.

65 By the provision of the wooden sides 3, wooden ends 4, and the wooden base 2, I 70 prevent undue radiation of the heat from the contents of the heating tank 7, which is extremely desirable in heated rooms such as are common in laundries.

75 By the provision of the copper or metallic facing 9 which covers the wooden top 8 of the table, it will be apparent that the top of the table is protected and strengthened and the wooden body and top being poor heat conductors, the heat is confined within the 80 tank.

85 By the provision of the valve 26 the amount of steam conducted to the steam loop formed by the branches 17, 18 and 19 can be regulated according to requirements, 85 so that the starch receptacles can be readily heated to the desired temperature. The pipe 13 can be extended to another table so that if steam is to be cut off from the table shown in the drawings, said valve 26 will be closed. 90

95 While I have shown my apparatus as designed to support several starch receptacles, it will be apparent that the number of openings 10 as well as the number of starch receptacles can be increased or diminished according to requirements.

100 It will now be apparent that I have devised a novel and useful construction of a steam or starch heater or table which embodies the features of advantage enumerated as desirable in the statement of the invention and the above description, and while, I have, in the present instance, shown and described a preferred embodiment thereof which has been found in practice to give 105 satisfactory and reliable results, it is to be understood that the same is susceptible of modification in various particulars without departing from the spirit or scope of the invention, or sacrificing any of its advantages. 110

Having thus described my invention what I claim as new and desire to secure by Letters Patent, is:—

115 1. In a starch heating apparatus of the character stated, a tank adapted to be heated composed of a body formed of sides, ends, a top and a bottom of wood, said top having an opening therein for the vessel to be heated, and a starching table on said top, the same being composed of a metallic plate, the same having an opening therein coincident with that in said top and having its sides extended beyond the sides of said body. 120

125 2. In a starch heating apparatus of the character stated, a tank adapted to be heated composed of a body formed of side, end and bottom walls of wood, said end walls being

jointed into the side walls, and said side walls being extended beyond said end walls, and bolts passing through the extensions of the side walls exterior of the end walls, said bolts having tightening devices thereon, said body having therein a starching table of metal, said table and top having coincident

openings thereon for the vessel to be heated, and said table having its sides extended beyond the sides of said body.
